LAWN SPRINKLER

Holstein W. Webb, Columbus, Ohio

Application June 15, 1934, Serial No. 730,683

19 Claims. (Cl. 299—106)

The invention to be hereinafter described relates to lawn sprinklers.

While the term lawn sprinkler includes any and all devices for sprinkling lawns, borders, hedges, etc. in any manner, the present invention is more particularly concerned with the mobile surface-pipe type which is adapted to be moved to a selected spot and there left for a short time until shifted to another selected spot, or cut off. One of the most widely known sprinklers of such type is the Skinner sprinkler which comprises a pipe length of twelve to eighteen feet or other desired size, to feed or supply the water to the nozzles. In practice, this pipe is mounted at one end on wheels or skids for easy handling. Throughout its length, it is provided with a plurality of small nozzles each with a threaded nipple to be turned into a corresponding bore in the pipe wall—as indicated in Fig. 3. In assembly, these nozzles are distributed throughout the surface of the pipe to dispose the jets, etc., as may be desired. Each nozzle is formed with a spray head or block having a plurality of removable spray surfaces, in some forms. In the Skinner, the spray surface is integral with the head. One type nozzle gives a simple jet, as through a small diameter free passage. A second presents a surface which intercepts the jet and spreads it fan-like. A third presents a broader surface at a sharper angle which breaks the jet into fine spray or "mist" over a wide low arc. Each nozzle is adapted to give but a single and unvarying delivery—jet, spray, "mist", etc. In order to change that, the nozzle must be changed, in Skinner, or the block on the nozzles must be changed in the others. That, of course, applies to each and every nozzle, any group of nozzles, and the entire set of nozzles. And too, it is obvious that the nozzles can not be changed during operation without getting the operator wet. Again, if it should be desired to give different types of spray and/or mist from the same pipe length or sprinkler, at the same time, as many sets of nozzles as types of spray and/or mist, will be required. And, of course, when so arranged, that particular assembly or set up becomes fixed and permanent until another assembly is made up for a changed distribution. In the Skinner and analogous systems, separate nozzles or separate surfaces are used for each respective type of spray, jet, or "mist", as disclosed by the following U. S. Patents:—868,775; 1,954,863; 1,639,162; 1,805,782; 1,837,595; with

which I am fully familiar. I am also familiar with U. S. Patents 977,748 and 1,795,807.

The present invention avoids all of the above objections and many others and provides a simple, compact, efficient and economical construction, arrangement and assembly of a single set of nozzles adapted to provide any desired delivery or combination of deliveries, and to vary that delivery in any desired manner during operation; and this without the removal of any nozzle.

In order to more clearly disclose the construction, operation and use of the invention, reference should be had to the accompanying drawing forming part of this application. Throughout the several figures of the drawing like reference characters designate the same parts in the different views.

In the drawing:—

Fig. 1 is a top plan view of one of the nozzles of this invention;

Fig. 2 is a side elevation of Fig. 1, looking toward its right side, with spring omitted;

Fig. 3 is a cross section on line 3—3 of Fig. 1, looking in the direction of the arrows;

Fig. 4 is a fragmentary cross section of a modification of the nipple of the nozzle;

Fig. 5 is an enlarged side elevation of the connection for operating a plurality of the nozzles simultaneously;

Fig. 6 is a plan view, reduced, of a plurality of nozzles assembled and connected for simultaneous operation, only a few being shown, and;

Fig. 7 is an enlarged fragmentary view of the wire-pull adjustment.

It is known, of course, that a jet of water impinging upon a surface is changed and that the resulting character of the delivery is dependent upon the surface impinged. When the jet impinges a flat narrow surface approaching parallelism to the axis of the jet, the resulting delivery becomes an elongated narrow fan. When the surface is widened and turned at a greater angle toward the jet axis, the resulting fan is shortened and widened. Continuing in the same way, results in fine mist of very broad and feathery fans. And so, as between the uninterrupted jet and the fine "mist" type of delivery, there may be a wide range of variations according to individual wishes, provided the right deflecting or impingement surfaces are provided or available.

By the present invention, any one of a group of such surfaces is instantly available, either individually, in groups, or as an entire set. For

purposes of illustration, but without in any degree limiting this application, the individual nozzles have been shown as provided with one free passage or straight jet channel and two impingement surfaces, one adapted to give a long-radius medium-width fans delivery spray and the other a very short-radius approximately maximum-width fan delivery or "mist." These are the three types of delivery most regularly in general use.

I shall first describe the individual nozzles, without regard to group or plural operation; following that with description of such groups and plural operation.

Referring to the drawing in detail, 1 indicates the usual and well known mobile sprinkler pipe one end of which usually is, though not essentially, mounted on wheels or skids, for readily moving from point to point. It is provided with the usual threaded openings for the usual nipples. As is well known, the friction on a jet of water through a small diameter opening is sufficient to appreciably reduce its delivery, even in the shortest practicable bore. As the length of bore increases, friction increases in well known ratio, with corresponding decrease in delivery. To reduce this friction to the minimum and correspondingly increase the efficiency in delivery, the present invention provides the thinnest practical wall through which the jet must issue, thereby giving the shortest practical jet-bore. This is clearly shown in Figs. 3 and 4, in which 3 represents the nipple, 4 the wall through which the jet issues and 5 the jet passage. It will be noticed that the nipple is of sufficient length to project a considerable distance, proportionately, into the interior of the pipe 1. It has been found that scale and sediment is greatest at the point where the nipple passes through the pipe. By extending the nipple inwardly beyond this point, it clears this scale and sediment and projects into the clear water current. The modification of Fig. 4 is a further protection against scale and sediment. In that form, the wall 4 constitutes the inner end of the nipple, thereby eliminating any cavity or pocket in which any sediment or scale may possibly collect. In addition, the outer surface of the inward nipple-end is rounded or convexed as at 6, to further avoid any possibility of scale or sediment lodging thereon. The inward edge of the nipple in the other form may be similarly rounded for a like purpose, of course.

Nipple 3 carries plate 7 on which is rotatably mounted a delivery control, spray forming block 8. The axis of rotation of block 8 is a post or pin 9 which is threaded into the plate 7 and is provided with a stop or limit shoulder 10 to prevent binding of the block 8 against the plate 7 when the pin is turned up tight. But, to give a yielding frictional hold or contact between 7 and 8, a coil spring 12 is provided. This is disposed about the pin 9 below head 11 and engages an annular inner shoulder 13. Spring 12 is of sufficient strength to force the block 8 into frictional holding contact with plate 7, so that appreciable though not great force is required to rotate the block. Thus, a yielding, frictional hold is provided to maintain the block in adjusted positions. For more positively holding the block in definite selected positions, a knob 14 is provided on plate 7 adapted to cooperate, selectively, with and be seated in any one of several corresponding small sockets 15 formed in the adjacent or contacting face or surface of block 8.

These sockets and the knob 14 are so positioned, relatively to each other and to the jet bore or passage, as to aline the center of the respective deflector face and the jet bore, in the same circumferential plane of the pipe, whenever a 5 socket is seated over the knob. Or, it may be stated that, in operative assembled relation, when a socket is seated over the knob, the axis of the jet bore and the center line of the then operative deflector face of the block will lie in 10 the same plane which is at right angles to the longitudinal axis of the pipe. Block 8, preferably, is formed as an inverted frusto-cone, with its larger diameter up. When assembled, the smaller circumference extends radially beyond 15 bore 5 and closes it.

For simplicity and clearness, only three operative surfaces are shown on the block. It may, of course, have a greater number and it may have surfaces of different constructions than 20 those illustrated. The application is not limited to either the number shown or to the particular type of construction of faces shown. As shown, block 8 is provided with a groove or channel 16 which, when turned into operative position, as in the drawing, provides a free and clear passage for the jet issuing through the passage 5, so that there is a long round jet exactly as though there were no block 8. The face of block 8 is cut back, channeled or grooved 25 deep enough to have its face or wall clear of and slightly spaced from the issuing jet. At either side of this jet channel, is a delivery regulating surface or jet impingement face. One of these faces 17 may be referred to as the 30 spray surface. It is made by passing a plane inwardly and downwardly from a point on the upper circumference to and through such a cord of the lower circumference as will, in the rotation of the block uncover the end of the jet bore 35 5, when the impingement face 17 reaches operative position. This provides a relatively long narrow elliptical surface projecting above and in the path of the issuing jet which impinges against it. The angle of impingement is slight. 40 The solid jet is slightly deflected circumferentially of the pipe 1 and spread into long narrow fan-shaped spray circumferentially narrow and radially long. The second impingement surface 45 is similarly made by passing a plane at an angle 50 of sharper degree to the face of the block 8, through the block, entering at a point between the upper and lower faces and cutting the lower face or circle by substantially the same length cord. As here shown, the point of entry of the 55 cutting plane is approximately half way between the top and bottom of block 8. The resulting impingement surface 18 is elliptical but of much greater or flatter curvature than face 17. It projects into the path of the jet at a much 60 sharper angle. Impingement against it is sudden and abrupt, the force of the impingement creating a "mist" which is dispersed in a circumferentially broad and radially short arc or fine, wide, feathery fan.

Block 8 may be provided with a tail or handle 19 by which it may be rotated, overcoming the action of spring 12, from one position to another to selectively present anyone of the three surfaces. It is to be understood, of course, that the 70 surfaces may be arranged in different order or succession than here given, that different surfaces than here illustrated may be used, and that a greater number and variety of faces or surfaces may be used. And, obviously, the rotatable block 75

5 may be cylindrical, polygonal, or of other shape instead of frusto-conical. The impingement surfaces would be formed accordingly, of course, to give the desired effect, the spray, or mist, in all instances being directed circumferentially of the pipe by the surfaces 17 and 18 or other surfaces performing the corresponding functions.

10 A plurality of these assemblies are mounted on each pipe 1. In fact, they are mounted on pipe 1 in just the same way and to the same number as are the well known Skinner nozzles. Or to put it a little differently, for each Skinner single-action nozzle may be substituted, in just the same way, one of my multiple action nozzles. Assume a pipe 1 fully equipped from end to end with a complete set of my multiple action nozzles. For simple straight jets they are all set with channels 16 in operative position; for spray, with impingement surfaces 17 in operative positions; and for "mist" with impingement surfaces 18 in operative position. Or, obviously, any two or all three types of delivery may be produced from the same pipe by merely correspondingly adjusting the blocks. Very beautiful and artistic effects may be had by such combinations, in addition to the utilitarian value.

15 For simultaneously operating them in multiple, each tail 19 may be connected to a single operating means carried by the pipe 1. This comprises a reciprocable wire 20 passing freely through the slot 100 of a clamping block or jaw 21 and held under tension by a spring 22 disposed about one end of the wire and held under compression between a head, block or the like 23 on the wire end, and a supporting clamp 24, secured in well known manner to pipe 1. Wire 20, of course, passes freely through clamp 24, as shown. The opposite end of the wire 20 is, after passing through a key-hole slot 25 of a clamp 26, provided with a pull handle 27. Wire 20 is provided with a set of stops in the form of collars or washers 28 which may be secured at any desired point on wire 20 by set screws 29 or the like. The large opening of the key-hole is great enough to permit passage of the stops but the small opening will not, though it will permit passage of the wire, all as will be readily understood. It will be clear then, that a pull on handle 27 will draw the wire 20 against the force of the spring 22. As soon as the first collar or stop 28 passes through its key-hole, the wire may be dropped so that the collar will be engaged by or against the clamp 26 and the wire held. Further pull may bring the second stop into similar holding position. When completely released, the spring 22 will return the wire in the opposite direction. To prevent too far a return, a stop 28 is similarly secured near the opposite end of the wire and positioned to engage clamping bracket 24 if the pull of the spring 22 would tend to pull or carry the wire too far in that direction.

20 Each tail 19 has a free swivelling connection with one of the blocks 21 by means of a headed bolt 30. Bolt 30 passes upwardly, in free turning or swivelling relation, through a suitable hole in the respective tail, its head 31 acting as an upward stop or limit and has its upper end 32 threaded into the block in such relation and to such extent as to engage and clamp the wire 20 in slot 100 of the respective block 21. In assembling for simultaneous operation by the pull wire 20, the wire is first released so that the spring is under least compression and the stop at that end engages the clamp 24. Next, 25 each individual block 8 is adjusted to the de-

sired position. For instance, with the surface 13 in operative position and every tail in its extreme position toward the right. Now, the wire is slipped into the slots in the blocks 21 and clamped by tightening the respective screw 5 bolts 30. A pull on the handle 27 draws the first stop 28 through the key-hole slot 25 and turns all blocks 8 to cut off the surface 18 and bring into play the jet opening or channel 16 of each. This is the position shown in Fig. 6. 10 A further pull to the next stop cuts off all jets and brings into play all sprays from surfaces 17. By releasing the wire to the action of the spring 22, it will be returned in the opposite direction to the starting point or position, with 15 all "mist" surfaces 18 in operative positions. In such battery or gang assemblies, the stops 28 are sufficient and the knobs 14 with cooperating sockets may be omitted, if desired. It is, of course, obvious that a greater or less number of the tails may be left unclamped and unaffected by the wire pull. It is equally clear that the blocks need not all be set for the same type of jet, spray or mist, at the start. Some may be set for one and some for another. If 25 they are set differently, as originally connected, then each operation of the wire will simply change all of them to the next respective position with corresponding change in respective jet, spray, etc. Clearly, other forms of stops 30 may be used for the wire.

20 The great advantage of the simple swivel of bolts 30 in tails 19 is avoidance of substantially all twisting, bending, kinking, etc., of the wire 20. As the tails 19 swing about pins 9, the wire 35 does not bend or curve, except very inappreciably near each end between that respective end and the point where the adjacent arm 10 is connected to the wire. Instead, except as stated, it moves in a straight line toward or from 40 the pins 9 throughout its whole length. Its movement is parallel to pipe 1. The extreme travel toward or from pipe 1 is only slight, and is readily accommodated by the flexibility of the wire and the spring 22. 45

25 It will be noticed that the wire is pulled in both directions. For that reason a wire is practical and a rod is not required. No stiffness is necessary.

30 It is believed that the construction, operation 50 and use of the invention will be clear from the preceding detailed description.

35 Many changes may be made in the construction, arrangement and disposition of the various parts of the invention within the scope of the 55 appended claims, without departing from the field of the invention, and it is meant to include all such within this application wherein only a preferred form and a single modification of one detail have been illustrated, purely by way 60 of example and with no thought of in any degree limiting the application thereby or thereto.

40 Having thus described my invention, what I claim and desire to protect by Letters Patent is:—

45 1. A sprinkler nozzle comprising a nipple provided with a jet delivery passage, a plate carried thereby, and a block rotatably mounted on said plate and provided with a plurality of delivery controlling surfaces directed radially of 70 the axis of rotation, and adapted to be selectively positioned to intercept an impinging jet issuing through the aforesaid passage.

50 2. A sprinkler nozzle comprising a nipple provided with a jet delivery passage, a plate carried 75

- thereby a block rotatably mounted on said plate and provided with a plurality of delivery controlling surfaces directed radially of the axis of rotation of said block, and means for securing 5 said block in selected adjusted positions, and adapted to be selectively positioned to intercept an impinging jet issuing through the aforesaid passage.
3. A sprinkler nozzle comprising an elongated 10 nipple having a restricted short jet-bore, a plate carried thereby, a block rotatably mounted on said plate and provided with a plurality of delivery controlling surfaces directed radially of the axis of rotation of said block and selectively 15 extending across the projected axis of said jet-bore, and means for securing said block in selected adjusted positions.
4. A sprinkler nozzle comprising a nipple, a plate carried thereby, and a block rotatable on 20 said plate and provided with a plurality of inclined and radially directed delivery controlling surfaces.
5. A sprinkler nozzle comprising a nipple, a plate carried thereby, a block rotatable on said 25 plate and provided with a plurality of inclined and radially directed delivery controlling surfaces, and means for selectively securing said blocks in adjusted positions.
6. In combination, a supply pipe, a plurality 30 of nipples adapted to be secured therein, a plate carried by each nipple, a block rotatable on each plate and provided with a plurality of radially directed delivery controlling surfaces, and means for selectively securing said blocks in adjusted 35 positions.
7. A sprinkler nozzle comprising an elongated nipple provided with an inwardly convexed inner end, a plate carried thereby, and a block rotatably mounted on said plate and provided with a plurality of delivery controlling surfaces directed radially of the axis of rotation of said block.
8. In combination, a supply pipe, a plurality 40 of nipples adapted to be secured thereto, a plate carried by each nipple, a block rotatable on each plate and provided with a plurality of circumferentially extending radially directed delivery controlling surfaces, and means for securing each of said blocks, respectively, in adjusted positions.
9. In combination, a supply pipe, a plurality 45 of nipples adapted to be secured therein, a plate carried by each nipple, a block rotatably mounted on each plate and provided with a plurality of radially directed delivery controlling surfaces, and means for simultaneously rotating said blocks.
10. In combination, a supply pipe, a plurality 50 of nipples adapted to be secured therein and each having a jet delivery passage therethrough, a plate carried by each nipple, a block rotatably mounted on each plate and provided with a plurality of radially directed delivery controlling surfaces, and means for simultaneously rotating said blocks in either direction to selectively 55 present respective delivery controlling surfaces of said blocks to respective impinging jets.
11. In combination, a supply pipe, a plurality 60 of nipples adapted to be secured therein and each having a jet delivery passage therethrough, a plate carried by each nipple, a block rotatably mounted on each plate and provided with a plurality of radially directed delivery controlling surfaces, and means for simultaneously rotating said blocks step-by-step to selectively 65 present respective delivery controlling surfaces of said blocks to respective impinging jets.
12. In combination, a supply pipe, a plurality 70 of nipples adapted to be secured therein and each having a jet delivery passage therethrough, a plate carried by each nipple, a block rotatably mounted on each plate and provided with a plurality of radially directed delivery controlling surfaces, means for simultaneously rotating said blocks, and means for selectively securing said blocks in adjusted positions to selectively present 75 respective delivery controlling surfaces of said blocks to respective impinging jets.
13. In combination, a supply pipe, a plurality of nipples adapted to be secured therein and each having a jet delivery passage therethrough, a plate carried by each nipple, a block rotatably mounted on each plate and provided with a plurality of radially directed delivery controlling surfaces, and means for simultaneously rotating a plurality of said blocks to selectively present respective delivery controlling surfaces of said blocks to respective impinging jets.
14. In combination, a supply pipe, a plurality 80 of nipples adapted to be secured therein and each having a jet delivery passage therethrough, a plate carried by each nipple, a block rotatably mounted on each plate and provided with a plurality of radially directed delivery controlling surfaces, a pull wire, and means for connecting each block to said pull wire for simultaneous operation of all said blocks to selectively present respective delivery controlling surfaces of said blocks to respective impinging jets.
15. In combination, a supply pipe, a plurality 85 of nipples adapted to be secured therein and each having a jet delivery passage therethrough, a plate carried by each nipple, a block rotatably mounted on each plate and provided with a plurality of radially directed delivery controlling surfaces, a pull wire, means for connecting each block to said wire for simultaneous operation of all said blocks, and means for securing said wire in adjusted positions to selectively present respective delivery controlling surfaces of said blocks to respective impinging jets.
16. In combination, a supply pipe, a plurality 90 of nipples adapted to be secured therein and each having a jet delivery passage therethrough, a plate carried by each nipple, a block rotatably mounted on each plate and provided with a plurality of radially directed delivery controlling surfaces, a pull wire, and swivel connections between each block and said pull wire for simultaneous operation of said blocks to selectively present respective delivery controlling surfaces of said blocks to respective impinging jets.
17. In combination, a supply pipe, a plurality 95 of nipples adapted to be secured therein and each having a jet delivery passage therethrough, a plate carried by each nipple, a block rotatably mounted on each plate and provided with a plurality of radially directed delivery controlling surfaces, a pull wire operable alternately in opposite directions, swivel connections between the respective blocks and said wire for simultaneous operation of the blocks connected thereto and means for securing said pull wire in adjusted positions to selectively present respective delivery controlling surfaces of said blocks to respective impinging jets.
18. In combination, a supply pipe, a plurality 100 of nipples adapted to be secured therein and

each having a jet delivery passage therethrough, a plate carried by each nipple, a block rotatably mounted on each plate and provided with a plurality of radially directed delivery controlling surfaces, a pull wire operable alternatively in opposite directions, swivel connections between the respective blocks and said pull wire for simultaneous operation of the blocks connected thereto to selectively present respective delivery controlling surfaces of said blocks to respective impinging jets, stops carried by said wire, and means engaged by said stops for holding said pull wire in adjusted positions.

19. In combination, a supply pipe, a plurality of nipples adapted to be secured therein and

each having a jet delivery passage therethrough, a plate carried by each nipple, a block rotatably mounted on each plate and provided with a plurality of radially directed delivery controlling surfaces, a pull wire operable alternatively in opposite directions, swivel connections between said respective blocks and the wire to selectively present respective delivery controlling surfaces of said blocks to respective impinging jets, stops carried by said wire, means for adjusting said stops, and means engaged by said stops for holding said pull wire in adjusted positions.

HOLSTEIN W. WEBB.
